ELECTRIC SWITCH

Frank H. Roby, Milwaukee, Wis., assignor to
 Square D Company, Detroit, Mich., a corpora-
 tion of Michigan

Application March 4, 1939, Serial No. 259,763

6 Claims. (Cl. 200—97)

This invention relates to an electric switch involving a plurality of contacts adapted to be sequentially engaged and disengaged with predetermined time intervals, and has for one of its objects the provision of an improved construction for such a switch which shall be of simple and economical construction while accurate in its operation.

Another object of this invention is to provide an improved operating means for an electric switch of this type.

Another object of this invention is to provide in an electric switch of the above type an improved and simplified means for effecting adjustment of the position of the stationary contacts to determine the periods between the sequential operations aforesaid.

Other objects and features of the invention will be readily apparent to those skilled in the art from the following specification and appended drawings illustrating certain preferred embodiments of the invention in which:

Figure 1 is a front elevational view of the electric switch according to the present invention.

Figure 2 is a vertical elevational view of the electric switch according to the present invention.

Figure 3 is an enlarged sectional view taken along line III—III of Figure 1.

Figure 4 is an enlarged vertical sectional view taken along the line IV—IV of Figure 1.

Figure 5 is an enlarged sectional view taken along the line V—V of Figure 1.

The electric switch according to the present invention comprises a supporting panel 1 having mounted thereon a plurality of relatively movable contact sets indicated generally at 2 and actuated in response to the energization of an electromagnet 3, with the timing of the actuation of the contacts in opposite directions determined by the settings of pneumatic time delay units 9 and 70. The operating parts of the time delay units 9 and 70 are duplicates but disposed to work in opposite directions and only that indicated at 9 is shown in detail. This comprises a supporting plate 5 secured to posts 6 as by studs 7, the posts being secured to the mounting panel 1 by studs 8. Upon the upper portion of the supporting plate 5 is mounted the timing unit 9 comprising a central dividing portion 10 having disposed therein a needle valve 11 and a check valve 12. The dividing portion 10 is of general double cup shape and to its bottom portion a flexible diaphragm 13 is sealably affixed thereto by means of a rigid metallic member 14. A nut 15 is secured to the diaphragm 13 by being riveted through opposite disc washers 16. A rod 18 is threaded into the nut 15 and is maintained in place by a locking nut 19. A flexible diaphragm 20 is connected

to the upper edge of the double cup member 10 by means of a rigid shielding member 21 having a relatively large opening 22 leading to the external air. The needle valve 11 includes a longitudinally adjustable pin 23 provided with gear teeth at its exterior portion 24 meshing with a large indicating wheel 25 pivotally attached to the supporting plate 5 and generally centrally thereof. It is to be noted that the timing element 9 provides for dash up movement by passage of the interior fluid through the check valve 12 and for delayed downward movement by the controlled passage of the interior fluid through the needle valve 11. The diaphragm 13 places the appropriate pressure or vacuum on the fluid within its chamber to secure movement of the fluid to or from its associated chamber through the valves and the diaphragm 20 is an idle diaphragm which acts as a reservoir for this fluid and serves to seal off the valves from the exterior air. Secured to the pin 23 and intermediate front bearing piece 26 and the gear teeth 24 is disposed a fiber disc 27. The fiber disc 27 is manipulable to rotate the pin 23 and the gear teeth 24 to move the indicating wheel 25 meshing therewith. A split spring pressed double bushing 28 holds the pin 23 and thereby the valve 11 in its adjusted position. Upon the lower end of the rod 18 is threaded a split attaching member 29 in which is secured a rigid insulating member 47 having mounted thereon and relatively movable with respect thereto spring biased contact elements 30, 31 and 32. The contact surfaces of bridging elements 30 and 31 face downwardly and the contact surfaces of the bridging element 32 face upwardly. The contact elements 31 and 32 are oppositely disposed and are directed away from each other toward stops 34 and 35 by means of a common biasing spring 33. The contact element 30 is biased downwardly with respect to the insulating member 47 and against stop 36 by means of a compression spring 37 disposed between the contact element and a washer 38 whose position is determined by the stop 39. As can be seen in the drawings, the contact elements 30 and 31 are engaged with their respective stationary contacts and move from their stops 36 and 35 respectively against the bias of springs 37 and 33 which maintain the contact pressure between the elements and their co-operating stationary contacts. Each of the bridging contact elements 30, 31 and 32 cooperates with a pair of spaced stationary contacts, certain of which are mounted for ready adjustment. These pairs of contact elements are mounted upon blocks 40, 41 and 42. Each of these stationary contacts includes a post 43 extending forwardly of the supporting insulating block and having mounted thereon a contact

surface 44 disposed upon a stud 45 threaded into the post 43 and maintained in place by a lock nut 46. The arrangement thus described not only provides means for mounting the stationary contacts, but also provides for adjustment of each stationary contact individually where desired. The bottom insulating block 40 is rigidly secured to panel 1 and supports the bottom end of guide rods 48 whose upper ends are rigidly secured to the panel. Two of these rods are provided, one being obscured by the member 47 as viewed in Figure 1. The contact supporting insulating blocks 41 and 42 are slidably mounted on the guide rods 48 and compression springs 49 are provided between the blocks to bias them apart. An adjustment rod 50 extends loosely through blocks 40 and 42 and is provided at either extremity with adjusting nuts 51 and 52. The central block 41 is tied to the rod 50 by a stud 53. With this arrangement it is seen that a means is provided for quick and easy adjustment of the position of the stationary contacts mounted on the blocks 41 and 42 merely by tightening or loosening the adjusting nuts 51 and 52 to shorten or extend the associated portion of the rod 50. In the adjustments, tightening of the adjusting nut 52 will cause the block 42 to move downwardly but will not move the rod 50, and hence will leave the central block 41 unaffected because of its attachment to the rod 50. The bottom block 40 will likewise be unaffected, being rigidly secured to the panel 1. Tightening of adjusting nut 51 will cause both the central and top blocks 41 and 42 to move downwardly in response to movement of the adjusting rod 50, which will carry these two blocks with it in its movement. Opposite rotation of the nuts 51 and 52 will cause similar movements of the blocks, but in the opposite directions.

An L-shaped bracket 54 is provided near the top of panel 1 and a compression spring 55 is disposed between the bracket 54 and a stop 56 on member 47 to bias the member in a downward direction. Since contacts to be operated by the member 47 at the extreme of its forward movement will ordinarily not need adjustment since they simply determine the final movement of the rod to deenergize its operating circuit, these contacts are here supplied in the form of a push button switch 4 which may be of conventional form and which is disposed with relation to a striker 58 rigid with the member 47 so that the striker 58 will move the push button of this switch to disengage these contacts near the extreme upward movement of the member. Since this push button switch may be of conventional form, its internal mechanism has not been specifically shown and is to be considered as simple additional switching contacts non-adjustable and operated at the upper extreme of the movement of the member 47. About the lower end of the member 47 is connected a guide and stop element 57 having an elongated pin portion 63 extending therefrom. This pin extends through and is guided by an insulated abutment 59 rigidly mounted upon a bracket 60 mounted on the panel. The enlarged portion of the element 57 contacts with the upper surface of the abutment 59 to determine the lower position of the member 47.

A cylindrical actuating member 61 guided by a rigid bracket 62 is disposed beneath pin 63 and is threaded at its lower end upon a rod 64 and locked thereon by a locking nut 65. The rod 64 is connected to the operating diaphragm

of the time delay unit 70 in a manner similar to that previously described for the operating diaphragm of the time delay unit 8. Disposed about the rod 64 is a compression spring 66 disposed between the locking nut 65 and a lateral arm 71 of a pivotal armature 67. With this arm in its lower or deenergized position, the spring 66 is substantially free of compression. The armature is stopped in its deenergized position by means of a position limiting bracket 68. The pole face of the armature is provided with a facing sheet of brass or other non-magnetic material 69 to prevent sealing of the armature in its energized position. For actuating the armature, there is provided a stationary or field magnet section 72 provided with operating coil 73 which, when energized, will effect the upward rotation of the armature 67.

The operation of the relay is as follows: Upon energization of the coil 73, the armature 67 will be rotated upwardly and will compress the operating spring 66. This will apply a spring bias to move the operator 61 upwardly and it will move in this direction at a rate dependent upon the adjustment of the time delay unit 70. When the operator 61 contacts pin 63, the member 47 will commence to move upwardly and will operate the contacts associated therewith in the following sequence: first, the stop 36 will engage the bridging contact 38 to effect opening of the circuit therethrough; secondly, the stop 35 will engage bridging contact element 31 to effect opening of the circuit therethrough; thirdly, contact element 32 will be moved into engagement with its cooperating stationary contacts to complete the circuit therethrough; and, fourthly, the striker 58 will engage the operating push button of the switch 4 to interrupt the circuit therethrough. When thereafter the coil 73 is deenergized either through the actual opening of the circuit through the switch 4 or in response to some other operating switch, the armature 67 will be released and moved downwardly whereupon the member 47 will start its downward movement under the combined action of gravity and biasing spring 55. In this downward movement, the speed of member 47 is controlled entirely by the setting of the time delay unit 8, it being understood that in the upward movement of the member, the timing unit 8 permits the free passage of the controlling fluid through the check valve and, in the downward movement of the operator 61, the time delay unit 70 permits the free passage of the control fluid through its check valve. In this downward movement of the member, the direction of the contacts will be reversed to that previously set forth; firstly, the striker 58 will release the operating push button of the switch 4 to close the circuit therethrough; thereafter the bridging contact 32 will be moved away from these stationary contacts in response to the engagement of the stop 34 therewith, and thereafter contacts 31 and 38 will, in that respective order, be engaged with their co-operating stationary contacts.

It is seen that in the operation of the switch there are four timing periods; first, the period from the energization of the coil 73 until the contact 38 is operated; second, the period between the operations of contacts 30 and 31; third, the period between the operations of contacts 31 and 32; and fourth, the time between the operation of contact 32 and the operation of the switch 4. There are, of course, other timing periods which might be considered inasmuch as

the time of closing of the contacts 32 is made up of the two periods involving the upward and downward movement of the rod and, similarly, the times of opening of the contacts 30 and 31 are made up of the two components due to the raising and lowering of the switch. Considering the four basic time intervals, adjustment of these could be had in various ways, but the simplest form of adjustment will be described. The first timing period, inasmuch as the stationary contacts cooperating with the bridging contact 38 are relatively permanently adjusted, will be determined by the adjustment of the time delay unit 70. The adjustment of this unit also transmits itself through the other timing periods, but these are otherwise adjustable whereas the first timing period is determined solely by this adjustment and the permanent adjustment of the position of the first set of stationary contacts. The second timing period between the operation of contacts 30 and 31 is determined by adjustment of the screw 51. This adjustment moves both contact blocks 41 and 42 and, hence, does not vary the third timing period, although it does change the fourth timing period. The third timing period is determined by adjustment of the nut 52 which moves the contact block 42 only to vary the time between the operation of contact 31 and contact 32. The fourth timing period is determined by the adjustment of both nuts 51 and 52, since both of these nuts effect movement of the contact block 42. The adjustment of the time delay unit 9 will similarly effect the speed of movement of the rod in the opposite direction and determine the time interval at which the operation of the contacts occurs.

While certain preferred embodiments of the invention have been specifically disclosed, it is understood that the invention is not limited thereto as many variations will be readily apparent to those skilled in the art and the invention is to be given its broadest possible interpretation within the terms of the following claims.

What is claimed is:

1. An electric switch comprising a movable member, a plurality of contacts movable in response to movement of said member, a plurality of stationary contacts adapted to be engaged and disengaged by their reciprocable movable contacts in response to movement of said member, means for relatively stationarily mounting one of said stationary contacts, means for adjusting the position of others of said stationary contacts with respect to said first stationary contact but without disturbing the relation between said others of said stationary contacts, and means for adjusting at least one of said other sets of contacts without disturbing the remainder of them.

2. An electric switch comprising at least three spaced stationary contacts, movable contacts cooperating with said stationary contacts, means for successively operating said movable contacts, means for relatively permanently mounting one of said stationary contacts, means for adjusting two of said stationary contacts with respect to said one stationary contact without disturbing the spacing between said two stationary contacts, and means for adjusting one of said two stationary contacts independently of the other.

3. An electric switch comprising at least three vertically spaced sets of horizontally spaced stationary contacts, a plurality of bridging contacts

adapted to cooperate with said horizontally spaced stationary contacts, a vertically movable member for actuating said bridging contacts, means mounting the first set of stationary contacts in a relatively permanent position, means for adjusting the spacing between said first and second set of spaced stationary contacts without disturbing the space between the second and third sets of stationary contacts, and means for adjusting the said third set of stationary contacts without disturbing the position of said first and second sets of said stationary contacts.

4. An electric switch comprising a stationary insulating block, a pair of spaced stationary contacts mounted on said block, a pair of movably mounted insulating blocks with pairs of stationary contacts mounted thereon, movable bridging contact members for cooperating with said pairs of stationary contacts, means for moving said bridging contacts to successively effect cooperation thereof with their respective pairs of stationary contacts, means for adjusting the pair of movable insulating blocks as a unit with respect to the stationary block, and means for adjusting one of said movable blocks while maintaining the other stationary.

5. An electric switch comprising a reciprocable member, a plurality of electrically independent sets of contacts adapted to be successively operated by said member in its movement in opposite directions, means establishing one set of contacts in a relatively fixed relation, means adjusting the interval between said stationary set and other sets of said contacts without disturbing the interval between said other sets, means for adjusting at least one of said other sets alone, an adjustable time delay means at each end of said member, each of said means delaying movement of said member in one direction only, an electromagnetic operator for said member comprising a field magnet and a pivoted armature, spring means interposed between said pivoted armature and said member and adapted to be stressed to apply a resilient force upon said member upon energization of said field magnet, the member moving in one direction through said resilient force under the control of one of said delay means, the other delay means controlling the speed of movement of said member in its return movement upon deenergization of said field magnet.

6. An electric switch comprising at least three vertically spaced sets of horizontally spaced stationary contacts, a plurality of bridging contacts adapted to cooperate with said horizontally spaced stationary contacts, a vertically movable member for actuating said bridging contacts, means mounting the first set of stationary contacts in a relatively permanent position, means for adjusting the spacing between said first and second set of spaced stationary contacts without disturbing the space between the second and third sets of stationary contacts, and means for adjusting the said third set of stationary contacts without disturbing the position of said first and second sets of said stationary contacts, time delay means for controlling the rate of movement of said member, electromagnetic operating means including a field magnet and a movable armature, and spring means operable by said armature to apply a resilient force effecting controlled movement of said member.

FRANK H. ROBY.
